ROCK DRILL

Filed Oct. 24, 1928

FIG.-1.

INVENTOR
William A. Smith Sr.
BY *Asst. Secy.*
HIS ATTORNEY

UNITED STATES PATENT OFFICE

WILLIAM A. SMITH, SR., OF EASTON, PENNSYLVANIA, ASSIGNOR TO INGERSOLL-RAND COMPANY, OF JERSEY CITY, NEW JERSEY, A CORPORATION OF GERMANY

ROCK DRILL

Application filed October 24, 1928. Serial No. 314,657.

This invention relates to rock drills, but more particularly to an improvement in the mode of securing such stationary elements as may be encased by the cylinder, as for instance, a valve chest and a rotation ratchet.

In rock drills of the fluid actuated type and in which such elements as a valve chest and the rotation ratchet are encased by the cylinder various expedients are employed for maintaining these elements in the correct operative position relatively to the cylinder. A method frequently employed for this purpose is to provide the valve chest, the rotation mechanism and the elements between which these parts are disposed with apertures so located that they will be in alignment in the assembled position of the parts. A key or pin is then disposed in the apertures to assure the correct relative positions of the parts.

Objectionable disadvantages result from this form of construction, such as losing the pin when disassembling the drill and the pin becomes battered during handling, thus frequently causing considerable delay in refinishing the pin or in supplying a substitute pin.

The present invention contemplates the elimination of the aforesaid undesirable features in structures of this type and one of its objects is to enable the rock drill to be readily assembled with a minimum of effort and time.

Another object is to eliminate extensive and costly machining operations on the parts intended to be secured in the drill.

Other objects will be in part obvious and in part pointed out hereinafter.

In the drawing showing a practical embodiment of the invention and in which similar reference characters refer to similar parts,

Figure 1 is an elevation of a rock drill partly broken away,

Figure 2 is a transverse view taken through Figure 1 on the line 2-2 looking in the direction indicated by the arrows, and

Figure 3 is a plan view of the back head of the drill showing the arrangement of the side bolts on opposite sides of the drill.

Referring more particularly to the drawing, A designates generally a rock drill com-

prising a cylinder B and front and back heads C and D respectively which are secured to the cylinder B by means of side bolts E. The side bolts E are disposed on diametrically opposite sides of the drill A and in this instance have heads F which seat upon the back head D. The opposite or forward ends G of the side bolts are threaded for the reception of nuts H, one on each bolt of which bears against lugs J of the front head for clamping the front head to the cylinder. The outer nuts H serve only as locking nuts for preventing unthreading of the nuts from the bolts E.

In accordance with the present invention an enlargement K is formed at the rearward end of the cylinder B, and in said enlargement K is a bore L for the reception of a valve chest O which forms in this instance a closure for the rearward end of the cylinder B.

The valve chest comprises in this instance a pair of plates P and Q having apertures R through which extends the rifle bar S whereby rotary movement may be transmitted to a hammer piston T in the cylinder B for the purpose of changing the position of the working implement (not shown) which the drill is intended to actuate.

The rifle bar S has the usual head U which carries pawls V adapted for engagement with a rotation ratchet W for inducing rotary movement of the working implement. The rotation ratchet W is interposed between the valve chest O and the back head D and, like the valve chest O, is encased by the enlargement K of the cylinder.

In order that the valve chest O and the rotation ratchet W may be conveniently held in the operative position in the bore L said rotation ratchet and valve chest are provided with notches X and Y in opposite sides thereof. These notches X and Y are so located that they will register with each other and also with apertures Z and b in the back head and the enlargement K respectively and through which the side bolts E extend. The notches X and Y engage the side bolts E thus assuring the correct position of the rotation ratchet W and the valve chest O with

respect to the adjacent parts or elements wherewith they are associated.

Due to the present invention the use of separate locking means for the valve chest and rotation ratchet has been entirely eliminated, and the side bolts E which are standard parts of drills of this type are utilized for the purpose of locking these elements securely to the drill.

10 I claim:

1. In a rock drill, the combination of a cylinder having apertures therein and a back head having apertures coaxial with the apertures in the cylinder, a rotation ratchet in the cylinder having notches, and side bolts extending through the apertures of the cylinder and back head and engaging the notches for holding the rotation ratchet in operative position relatively to the cylinder.

20 2. In a rock drill, the combination of a cylinder and a back head having apertures, an enlargement on the cylinder having apertures to register with the apertures in the back head, side bolts for clamping the cylinder and the back head together, a valve chest in the cylinder, and a rotation ratchet interposed between the valve chest and the back head, said valve chest and said rotation ratchet having notches engaging the side bolts for holding the rotation ratchet and the valve chest in operative position in the cylinder.

In testimony whereof I have signed this specification.
